(57) **CLAIM**

The ornamental design for a wall-mounted ventilation hood, as shown and described.

DESCRIPTION

FIG. 1 is a front view of a wall-mounted ventilation hood showing my ornamental design;

FIG. 2 is a left view thereof in an open position;

FIG. 3 is another left view thereof in a closed position;

FIG. 4 is a top view thereof in the closed position; and,

FIG. 5 is top view thereof in the open position.

The bottom and rear views of the hood are not shown and form no part of the claimed design.

FIG. 2 includes an enlarged detail view of a portion of the hood.
